UNITED STATES PATENT OFFICE

ALBERT INDECK, OF CHICAGO, ILLINOIS

WINDOW SCREEN OPERATOR

Application filed December 13, 1930. Serial No. 502,046.

This invention relates to screens and more particularly to window screens, although certain features thereof may be employed with equal advantage for other purposes.

It contemplates more especially the provision of built-in screens for automatic concealment and exposure operable responsive to window displacement, thereby precluding removal or attachment during the different seasons of the year.

Numerous types of roll screens have heretofore been proposed but these have not proven especially advantageous owing to the intricate character of the operating devices. It is manifest that simplicity of construction and dependable operation thereof must be attended with minimum wear of the moving elements thereof.

One object of the present invention is to simplify the construction and improve the operation of devices of the character mentioned.

Another object is to provide roll screens for permanent attachment to windows so as to accomplish the dependable operation thereof responsive thereto with minimum wear.

Still another object is to provide simple, dependable and inexpensive operating means for built-in window roll screens.

A further object is to provide a novel and durable window screen operating mechanism.

A still further object is to provide novel means for effecting window screen operation without resort to expensive or intricate instrumentalities.

Still a further object is to provide window screen operating means of simple and dependable construction for synchronized operation with window displacement.

Other objects and advantages will appear from the following description of an illustrated embodiment of the present invention.

In the drawings:

Figure 1 is a front view in elevation of a device embodying features of the present invention, parts thereof being broken away to clarify the showing.

Figure 2 is a plan view of the device shown in Figure 1 with parts thereof removed to clarify the disclosure.

Figure 3 is an end view of the device shown in Figure 1 with the window frame siding removed to reveal the operating mechanism.

Figure 4 is an enlarged sectional view taken substantially along line IV-IV of Figure 1.

The structure selected for illustration comprises a window frame 10 of standard or approved construction with the stiles 11 thereof properly grooved for receiving the customary lower and upper window sashes 12 and 13, respectively. The window sashes 12 and 13 are maintained within the stiles 11 for slidable displacement owing to the retaining guide members 14 nailed or otherwise attached to the stiles 11. As shown, the window sashes 12 and 13 are provided with transparent window panes 15 and 16, respectively, to serve as a closure therefor in accordance with modern and standard practice.

The window frame 10 is provided with side and end housings 17 and 18, respectively, and these are completely enclosed by properly shaped and sized board sidings 19 nailed or otherwise joined in any suitable manner as commercial practice may dictate. End stiles 20 enclose the housing 18 to serve as a stop for the window sashes 12 and 13 in their extreme closed positions, thereby shielding the opening defined by the frame 10 against the elements. The usual sill 21 is provided immediately above the lower end housing 18, thereby approximating the structure of the standard window frame in every visual respect.

Suitable counter-weights for the sashes 12 and 13 may be provided or these may be dispensed with to meet any particular situation or desired condition of operation.

In order to provide summer closures for the openings defined by the frame 10 responsive to the displacement of the sashes 12 and 13 from their normally closed positions, intermeshed wire strands defining flexible screens 22 and 23 are attached in any suitable manner to the sashes 12 and 13, respectively, for operation responsive to the displacement thereof from their normally closed position, thereby serving as closures for the openings created in consequence thereof. The screens

22 and 23 are anchored to cylindrical rollers 24 and 25 journalled in suitable brackets 26 disposed interiorly of the housing 18 for attachment to the end stiles 20. In consequence thereof, the rollers 24 and 25 are completely concealed from view for rotary movement around a transverse axis in parallelism with the edges of the sashes 12 and 13.

As shown, the screens 22 and 23 are wound around the rolls 24 and 25, respectively, for attachment along an edge thereof by means of any suitable fasteners. The other edges 29 of the screens 22 and 23 are lodged within transverse grooves 30 provided in the corresponding lower and upper edges 31 of the window sashes 12 and 13, they being anchored therein by any suitable fasteners 32. Horizontally disposed bars 33 are seated within the window sash grooves 30 in adjacent contact with the screen edges 29 for attachment by means of the fasteners 32 thereof. The bars 33 have lateral extensions 34 which project within the side housing 17 through the stile slots 35, and the screens 22 and 23 also extend laterally for disposition within the stile slots 35, thereby completely closing the opening defined by the displaced window sashes 12 and 13 to preclude the entrance of flies and foreign substances prevalent in the atmosphere.

In order to operate the screens 22 and 23 responsive to the displacement of the window sashes 12 and 13, aligned sprockets 36, in this instance four, are attached to the extremities 35 of the rollers 24 and 25 beyond the brackets 26 for confinement in the side housings 17, the sprockets 36 on the respective rollers being in vertical alignment for mesh with flexible chain members 37. As shown, the chain members 37 mesh with the teeth of the sprockets 36, and the diametral meshing engagement thereof is substantially equal to the diameter of the rollers 24 and 25 with the screenings 22 and 23, respectively, thereon. In consequence thereof, the bar extremities 34 may be attached to the chain members 37 as at 38 to displace the screens 22 and 23 without any strains or stresses thereon responsive to the corresponding displacement of the window sashes 12 and 13. This operation is enabled owing to the fact that the linear movement of the screens 22 and 23 is substantially the same through the length thereof with the synchronized or corresponding displacement of the window sashes 12 and 13. This is accomplished by virtue of the diametral equivalency between the sprockets 36 and rollers 24-25 so that corresponding operation is effected responsive to manipulating one or the other of the window sashes 12-13.

It is possible to provide flexible metallic strips 39 as interposed members connecting the chains 37 to constitute an endless member tensioned about the aligned sprockets 36 in

each of the side housings 17. The extent of the stile slots 35 serves as a limit for the window and screen displacement in that contact with the bar extremities 34 serves as a stop therefor. It is to be noted that this arrangement affords very simple, inexpensive and dependable operating instrumentalities, and that the window sashes 12 and 13 may be synchronized for corresponding displacement in opposite directions, or these may be independently operated by resort to idler sprockets or pulleys in an obvious manner without departing from the spirit of the invention.

Various changes may be made in the embodiment of the invention herein specifically described without departing from or sacrificing any of the advantages of the invention as defined in the appended claims.

I claim:

1. In a device of the character described, the combination with a window frame, of an upper and a lower sash slidable in said frame, rollers journalled in said frame beyond the extreme closed edge movement of said sashes, screens wound around said rollers for edge attachment to said sashes, aligned sprockets axially fixed to the ends of said rollers, endless chain members in mesh with the aligned sprockets, and means for connecting said sashes with said endless chain members.

2. In a device of the character described, the combination with a window frame, of an upper and lower sash slidable in said frame, rollers journalled in said frame beyond the extreme closed edge movement of said sashes, screens wound around said rollers for edge attachment to said sashes, aligned sprockets axially fixed to the ends of said rollers, said sprockets and rollers having substantially the same diameter, endless chain members in mesh with aligned sprockets, and means for connecting said sashes with said endless chain members.

3. In a device of the character described, the combination with a window frame, of an upper and a lower sash slidable in the stile of said frame, rollers journalled in said frame beyond the extreme closed edge movement of said sashes, screens wound around said rollers for edge attachment to said sashes, aligned, sprockets axially fixed to the ends of said rollers, endless chain members in mesh with aligned sprockets exteriorly of said stiles, and means for connecting said sashes with said endless chain members.

4. In a device of the character described, the combination with a window frame, of an upper and lower sash slidable in the stile of said frame, rollers journalled in said frame beyond the extreme, closed edge movement of said sashes, screens wound around said rollers for edge attachment to said sashes, aligned sprockets axially fixed to the ends of said rollers, endless chain members in mesh with

aligned sprockets exteriorly of said stiles, there being slots in said stiles, and rigid members fixed to said sashes for extension through said slots to connect with said endless chain members.

5. In a device of the character described, the combination with a window frame, of an upper and lower sash slideable in the stile of said frame, rollers journaled in said frame beyond the extreme closed edge movement of said sashes, screens wound around said rollers for edge attachment to said sashes, aligned sprockets axially fixed to the ends of said rollers, endless chain members in mesh with aligned sprockets exteriorly of said stiles, there being slots in said stiles, rigid members fixed to said sashes for extension through said slots to connect with said endless chain members, and side housings on said frame for 0 confining said sprockets and chain members.

6. In a device of the character described, the combination with a window frame, of an upper and lower sash slideable in the stile of said frame, rollers journaled in said frame beyond the extreme closed edge movement of said sashes, screens wound around said rollers for edge attachment to said sashes, aligned sprockets axially fixed to the ends of said rollers, said sprockets and rollers having substantially the same diameter, endless chain members in mesh with aligned sprockets exteriorly of said stiles, there being slots in said stiles, rigid members fixed to said sashes for extension through said slots to connect with said endless chain members, and side housings on said frame for confining said sprockets and chain members.

In witness whereof I subscribe my name.
ALBERT INDECK.
